UNITED STATES PATENT OFFICE

169,317

PITCHER OR SIMILAR ARTICLE

Andrew C. Karlstad, Sherman Oaks, Calif., assignor to Enterprise Manufacturing Company, Inc., Burbank, Calif.

Application April 26, 1952, Serial No. 19,490

Term of patent 3½ years

(Cl. D44—21)

To all whom it may concern:

Be it known that I, Andrew C. Karlstad, a citizen of the United States, residing in Sherman Oaks, in the county of Los Angeles, State of California, have invented a new, original, and ornamental Design for a Pitcher or Similar Article, of which the following is a specification, reference being had to the accompanying drawing forming a part thereof.

Figure 1 is a front perspective view of a pitcher showing my new design.

Figure 2 is a side elevational view.

Figure 3 is a front elevational view.

Figure 4 is a top plan view.

I claim:

The ornamental design for a pitcher or similar article, substantially as shown.

ANDREW C. KARLSTAD.
